UNITED STATES PATENT OFFICE.

MELVIN L. STONE, OF PROVIDENCE, RHODE ISLAND, ASSIGNOR TO THE ESMOND MILLS,
OF ESMOND, RHODE ISLAND, A CORPORATION OF MASSACHUSETTS.

CLOTH TRIMMER FOR LOOMS.

Application filed July 28, 1927. Serial No. 203,928.

The invention relates to looms and more particularly to looms in which a plurality of filling yarns having different characteristics, such as different colors, are used in predetermined grouping in the weaving operation to produce predetermined effects in the woven fabric, such looms being exemplified by the conventional box looms. In weaving fabrics upon looms of this general class portions 5 of the various filling yarns are developed in the form of loose loops along the selvedge as a result of the fact that the different filling yarns are periodically woven into the fabric and in the interim are not used. These 10 filling loops are required to be cut away in order that the selvedge of the fabric may present the desired finished appearance. The object of the invention is to provide a fabric trimmer of novel and simple construction 15 whereby the fabric, as the weaving progresses, is automatically and efficiently trimmed along the selvedge to cut away such filling loops. Other objects will appear from the description hereinafter and the features of novelty 20 will be pointed out in the claims.

In the accompanying drawings, which illustrate an example of the invention without defining its limits, Fig. 1 is a plan view of the cloth trimmer; Fig. 2 is a side elevation 30 thereof; Fig. 3 is a corresponding elevation showing the parts in another position; Fig. 4 is a sectional view on the line 4—4 of Fig. 1; Fig. 5 is an end view, and Fig. 6 is a section on the line 6—6 of Fig. 4.

As shown in the drawings the trimmer comprises a temple 10 of any customary construction including an arm 11 which supports a transversely extending bracket 12 forming an integral part of or supporting a bar 13, the free end of which is mounted in a bracket 40 14 detachably fixed upon the temple 10 by means of screws 15. The bar 13 carries rollers 16 and 16^a over which an endless belt 17 travels, said belt being provided with a plurality 45 of series of prongs 18 or other equivalent devices as shown in Figs. 2, 3 and 4; the upper run of the belt 17 travels over and in close proximity to a flange 19 projecting transversely from the bar 13 as shown in Fig. 5. A retaining device 20 illustrated in the 50 form of parallel wires extends lengthwise of the belt in close proximity to the outer surface of the upper run thereof and has its one end secured by means of a screw 21 upon a lug 22 projecting from the bar 13 and its

other end directed downwardly as indicated at 23 and fastened to a member 24 secured to the arm 11 by means of screws 25 and extending transversely across the belt 17. The member 24 is continued in the form of a downwardly extending guide 26 located in tangential proximity to a plurality of rings 27, the axes of rotation of which preferably are inclined with respect to the axes of the rollers 16. The rings are provided with pins or 60 prongs 28 and constitute the customary fabric retaining means found in looms of the kind to which the invention relates. A roller 29 provided with prongs 30 is rotatably mounted by means of a square shaft 29^a upon a bracket 70 31 projecting from the bar 13 and is located in axial registry with the one roller 16 as shown in Fig. 1; the shaft 29^a is connected to move with the belt roller 16. The device further comprises a cutting instrumentality 75 consisting of a stationary knife 32 fixed in proper position upon the bar 13 and a cooperating movable cutter 33 pivoted at 34 upon said bar and preferably consisting of a double knife movable across opposite sides of the 80 stationary knife 32. The cutter 33 is carried by a pivoted member 35 acted upon by a spring 36 in a manner to maintain the cutting knife 33 in its normal position and to return it thereto as shown in Fig. 2. The movement 85 of the knife 33, under the influence of the spring 36, is arrested by means of a stop 33^a. An abutment screw 37 is adjustably mounted upon a lever 38 which is pivoted at 39 upon a lug 40 projecting upwardly from the bar 13. 90 The lever 38 carries a pivoted shoe 41 constituting a yarn guide and adapted to engage and rest upon the surface of the bar 13 to guide the filling to the belt 17 as will appear more fully hereinafter. A spring 42 95 acts upon the lever 38 to cause the screw 37 to follow the cutting movements of the knife 33.

The trimmer is particularly adapted for use in looms which are used primarily for 100 weaving fabrics having a plurality of differently colored filling yarns woven into the same. In such looms the shuttles carrying the different filling yarns become periodically active to carry said filling through the 105 shed to produce the desired effects, and then become inactive for a period of time until the particular filling yarns carried thereby are again required in the weaving process; these shuttles are carried upon the side of 110

the loom in the customary manner and are shifted into and out of operation in the conventional way. As the shuttles occupy temporary positions of rest, the filling yarns ⁵ *a*, *b* and *c* carried by the different shuttles extend outwardly from the edge of the fabric *d* as indicated in Fig. 1 and are carried along as the finished fabric *d* is wound upon the cloth roll in successive steps corresponding ¹⁰ to the laying or beating of the filling threads by the beater 43. As said shuttles are periodically brought into operation, loops of filling yarn, indicated by the reference character *e*, are formed along the selvedge of the fabric, said loops extending from that point in the fabric *d* where the particular shuttle temporarily become inoperative to the point in said fabric where said particular shuttle again came into operation. ¹⁵ In the present case the filling yarn in the loops *e* is caused to be looped over the prongs or pins 18 of the belt 17 as shown in Fig. 1 so that said loops are held thereby in position to be cut away as will be pointed out ²⁰ more clearly hereinafter. As the woven fabric *d* is wound upon the customary cloth roll the roller 29 will be rotated by the advancing fabric which becomes caught upon the prongs 30 and thereby causes the belt 17 to ²⁵ be advanced in corresponding steps, the fabric *d* being meanwhile held in its predetermined path by the rings 27 and the roll 29 in the well known way. This will cause a corresponding advance of the fillings *a*, *b* ³⁰ and *c* which pass successively beneath the shoe 41, and of the loops *e* which pass beneath the device 20 whereby said loops are held in engagement with the upper run of the belt 17 and finally pass over the stationary ³⁵ knife 32 and beneath the raised knife 33. Each time the lay 43 advances to lay the filling yarn, the arm 35 will be engaged by the lay 43 as indicated in Fig. 2 to swing said arm against the tension of the spring 36 to the ⁴⁰ position shown in Fig. 3. This causes the cutter 33, in co-operation with the knife 32, to sever or cut the loops *e* and to accordingly trim the woven fabric along its selvedge. The severed loops indicated as *e'* in Fig. 1 ⁴⁵ are carried along by the belt 17 beneath the devices 20 and finally drop from the same as said belt passes over the one roller 16. As the lay moves in a return direction, the spring 36 will return the arm 35 and cutter 33 to the ⁵⁰ position against the stop 33^a as shown in Fig. 2; at the same time the stop 37 will be raised until the shoe 41 comes again into engagement with the bar 13. It will be understood that in the case of a pick and pick loom the ⁵⁵ device illustrated and described herein may be duplicated upon opposite sides of the loom so that the opposite selvedge edges of the fabric are coincidentally trimmed in the manner set forth.

⁶⁵ The device is extremely simple in construc-

tion and efficient in operation and positively cuts away the loops *e* and thereby trims the fabric along the selvedge edges in a reliable and uniform manner. In addition, the loops *e*, being held by the prongs or pins 18, are ⁷⁰ prevented from becoming entangled with or woven into the fabric *d*.

Various changes in the specific form shown and described may be made within the scope of the claims without departing from the ⁷⁵ spirit of my invention.

I claim:

1. A trimming device for looms comprising a device adapted to travel continuously in the same direction lengthwise of the selvedge of the woven fabric, means carried by said traveling device for retaining loops of filling yarn formed at the selvedge in the weaving process, and a cutting device automatically operated for cutting said filling yarn loops close to the selvedge edge of the fabric. ⁸⁰ ⁸⁵

2. A trimming device for looms comprising an endless belt, prongs projecting outwardly from said belt and adapted to retain loops of filling yarn formed along the selvedge of the woven fabric, and a cutting means controlled by the lay of the loom for severing said filling yarn loops along the selvedge of said fabric. ⁹⁰

3. In a trimming device for looms, the combination of an endless belt arranged to travel in close proximity to the selvedge of the woven fabric, prongs projecting from said belt and arranged to retain loops of filling yarn formed along the selvedge of said fabric in the weaving process, a stationary retaining device extending over and in close proximity to the upper run of said belt, a stationary cutter, and a movable cutter controlled by the lay of the loom for cutting said loops of filling yarn along the selvedge edge of said woven fabric. ⁹⁵ ¹⁰⁰ ¹⁰⁵

4. In a trimming device for looms, the combination of an endless belt arranged to travel in close proximity to the selvedge of the woven fabric, prongs projecting from said belt and arranged to retain loops of filling yarn formed along the selvedge of said fabric in the weaving process, a stationary retaining device extending over and in close proximity to the upper run of said belt, a stationary cutter, a movable cutter controlled by the lay of the loom for cutting said loops of filling yarn along the selvedge edge of said woven fabric, a spring for maintaining said movable cutter in its normal position and for returning it thereto, and an adjustably mounted shoe for guiding outwardly extending filling yarns to said belt. ¹¹⁰ ¹¹⁵ ¹²⁰

5. In a trimmer device for looms, the combination of an endless belt arranged to travel in close proximity to the selvedge of the woven fabric, prongs projecting from said belt and arranged to retain loops of filling yarn formed along the selvedge of said fabric in the weaving process, a stationary retaining ¹²⁵ ¹³⁰

device extending over and in close proximity to the upper run of said belt, a stationary cutter, a movable cutter controlled by the lay of the loom for cutting said loops of filling yarn 5 along the selvedge edge of said woven fabric, a spring for maintaining said movable cutter in its normal position and for returning it thereto, an adjustable abutment screw, a piv-

oted member carrying said screw, and a shoe carried by said member for arresting the pivotal movement thereof and for guiding outwardly extending fitting yarns to said belt. 10

In testimony whereof I have hereunto set my hand.

MELVIN L. STONE.
